Specification for Design.

Patented Nov. 15, 1921.

Application filed August 19, 1921. Serial No. 493,756. Term of patent 7 years.

To all whom it may concern:

Be it known that I, ANTHONY H. ULRICH, a citizen of the United States, residing at Bloomington, in the county of McLean and State of Illinois, have invented a new, original, and ornamental Design for Finger-Rings, of which the following is a specification, reference being had to the accompanying drawing, forming part thereof.

Figure 1 is a top plan view of a ring, showing my new design.

Fig. 2 is an elevation of one side of the ring.

Fig. 3 is an elevation of the other side of the ring.

Fig. 4 is a bottom plan view.

I claim:

The ornamental design for a finger ring, as shown.

ANTHONY H. ULRICH.
